UNITED STATES PATENT OFFICE

ANICETO R. VISITACION, OF NEW YORK, N. Y., ASSIGNOR OF ONE-THIRD TO GENERAL WILLIAM WEIGEL AND ONE-THIRD TO LOUIS G. WEIGEL, BOTH OF NEW YORK, N. Y.

VENDING MACHINE

Application filed April 26, 1928. Serial No. 272,893.

This invention relates to vending machines of the type adapted for manual operation upon the insertion of a coin.

The constantly increasing number of such mechanisms, for dispensing an endless variety of small objects without the assistance of a salesman, their convenience and availability at all hours, and other advantageous features, is conclusive evidence of appreciation by the public.

However, most devices for such purposes are quite complicated in their construction, entailing expense and frequent failure in performing their function.

It is therefore an object of the present invention to provide an unusually simple device that, unless breakage occurs or the goods become exhausted, will unfailingly function in the vending of the articles to be sold.

A further feature is in the provision of means, which upon the entry of a coin and depression of a lever, will liberate a single article from the goods magazine and present it in an accessible position.

Another aim is to produce a neat appearing, compact mechanism having means to dispense a single article from any one of a series of magazines, containing similar goods but of unlike brands, selectively, by operation of a single element common to all, the present construction being designed to dispense cigarettes.

These objects are attained by the novel design, construction and combination of parts, hereinafter described and shown in the accompanying drawing, forming part hereof, and in which:

Figure 1 is a longitudinal sectional view of an embodiment of the invention.

Figure 2 is a partial front elevational, partial sectional view of the same, the section being taken on line 2-2 of Figure 1.

A rectangular casing is generally designated by the numeral 10, having an outwardly curved front wall 11 at its lower portion and a panel 12 thereover held in a frame 13.

At intervals along the lower part of the front wall 11 are outstanding arcuate guards 14, corresponding in number to that of the goods magazines, and below the guards are

openings 15 to permit insertion of the fingers in removing a cigarette X from the machine.

The bottom wall 16 of the casing has upturned front ledges 17 curved to suit the openings 15 and adjacently rearward of the ledges are perforations 18 acting as a drain for water, should it be driven in by storms through the openings 15.

Fixed in the casing 10 are the side walls 19 of the goods magazines, the same being flanged inwardly at their side edges, as at 20, presenting spaces 21 therebetween, these magazines being suited to contain a single vertical row of cigarettes pressed down by weights 22 having squared ends 23 slidable in the spaces 21 which act as guides.

Fixed to the front ends of the weights 22 are forwardly extending supports 24 carrying signs 25 as "Empty", the same showing through a transparent plate 12' in the panel 12 and indicating an exhausted condition of the magazine when the sign reaches a predetermined point.

Below and to one side of the magazines are curved guards 26 extending downwardly and terminating in straight elements 27 forming one of the side edges of chutes 28 directed downwardly at their front ends to extend to the ledges 17, these chutes receiving the goods X and directing them into an accessible position at the front of the machine, the other side walls 29 of the chutes extending upwardly and rearwardly, as best seen in Figure 2.

Fixed to the end elements 20 of the magazines are discs 30 in which are mounted axial spindles 31 carrying cylinders 32 having longitudinal grooves 33 adapted to receive one of the cigarettes from the magazine and, as the cylinder is turned, deposit it eventually in the chute 28.

Secured to the outer portions of the spindles 31 are blocks 34, generally rectangular, having ledges 35 at their longitudinal edge corners, the flat parallel sides of the blocks being positioned with reference to the cylinder recesses 33. The discs 30 contain spaced peripheral recesses 30' receptive of flat bowed springs 36, fixed at their lower ends to the

walls 29 of the chute, to act as detents for the cylinders.

Mounted in the casing sides, near its rear wall, is a rod 37 on which are pivotally engaged a series of levers 38, one for each magazine, these levers having raised lugs 39 carrying a rod 40 to which is attached one or more tension springs 41 fixed at their outer ends to a rod 42 carried in the side elements of the casing.

All of the several levers 38 terminate within the front wall 11 except one which extends through a slot 43 in the wall 11, preferably at the center of the casing, the single extending lever terminating in a handle 44, which, as will be seen, moves all the levers simultaneously when actuated.

A guard plate 45, carried by the extending lever, closely against the inner surface of the wall 11, serves to cover the slot 43, preventing the entrance of objects therethrough, irrespective of the position of the lever handle 44.

Extending rigidly towards the front from each of the magazines nearly to the wall 11, are flat plates 47 disposed adjacent one side of slots 48 in the front wall 11, through which may be entered coins C, these slots having at their ends spring elements 46 between which the entered coins must be pressed with considerable force and which prevent refraction of a partially entered coin.

At the opposite side of these slots are registering plates 49 carried by pairs of pins 50 slidably mounted in downturned portions of the levers 38 and also in angular brackets 52 rigidly attached to the upper edges of the levers 38, these pins 50 and plates 49 being pressed towards the plates 47 by compression springs 53, stops 54 limiting their outward movement.

Rearward of the coin entrance slots 48 are stops 55 preventing an excessive movement of the coins and serving to position them centrally between the fixed plates 47 and spring pressed slideable plates 49, so that the coin will rest upon the upper exposed surface of the block 34 in contact with its corner ledge 35.

When the coin, as a cent, has been properly entered through the slot of the compartment containing the selected brand of cigarettes, the single handle 44 is pressed forcibly downward, causing the entered coin to turn the block a predetermined part of a revolution, the coin moving outwardly with the spring pressed plate 49 until freed of the plate 47 and then dropping by gravity free of the block.

The cylinder 32 turns with the block, thus dispensing the cigarette contained in its lowermost groove, and the cigarette, dropping by gravity, is obtained from the chute 28 through the opening 15. At the same time another cigarette enters the groove in the cylinder, presented uppermost and in register

with the opening at the bottom of the magazine.

As the cigarettes are pressed down by the weight 23, the cylinder will be kept constantly supplied until the last has been sold, at which time the sign 25 appears and visually announces such condition.

In order to prevent coins from being entered when the machine is empty a shield plate 57 is fixed to each of the supports 24, so that as the weight 22 descends to bring the sign 25 into view, the shield 57 will become lowered, covering the opening 48 from the inner side of the casing and prevent entry of a coin.

The coins, after causing rotation of the block, fall by gravity into the casing to remain until removed by a properly authorized person.

The space at the rear of the casing may be utilized by a humidor 56 or like moisture producing means to maintain the tobacco in the cigarettes in a proper desirable condition for smoking.

Although the preferred embodiment of this invention has been described in detail, it is understood that minor changes in construction and details thereof may be made without departing from the scope of the appended claims.

Having thus described my invention, what I claim as new and desire to secure by Letters Patent, is:—

1. An actuator for a vending cylinder comprising a block at one end of the cylinder, said block having means to engage the lower edge of an entered coin, a fixed guide at the side of the coin, offset from the axis of said block, a spring raised lever having a part to contact the opposite side of the coin, and a part to engage the upper edge thereof to cause a partial revolution of said block and cylinder upon depression of said lever.

2. An actuator for a vending cylinder comprising a block at one end of the cylinder, said block having means to engage the lower edge of an entered coin, a fixed guide at the inner side of the coin, offset from the axis of said block, a lever, a pad carried thereby to contact the outer side of the coin, resilient means carried by the lever to press the pad against the coin, and means on said lever to contact the upper edge of the coin and cause it to turn about the axis of said block when the lever is depressed.

In testimony whereof I affix my signature.

ANICETO R. VISTACION.
